VEHICULAR SAFETY DEVICE OR THE LIKE

Kenneth D. Kramb, Portage, and Walter J. Isabell, Kalamazoo, Mich., assignors to K.I.C. Incorporated, Kalamazoo, Mich.

Filed Nov. 10, 1972, Ser. No. 305,366

Term of patent 14 years

Int. Cl. D12—16

U.S. Cl. D12—7

FIG. 1 is a front perspective view of our vehicular safety device or the like showing our new design;

FIG. 2 is a top plan view of our vehicular safety device or the like;

FIG. 3 is a side elevational view of our vehicular safety device or the like; and

FIG. 4 is a front perspective view of a vehicular safety device or the like showing a second embodiment of our new design.

The vehicular safety device, or the like, is mounted to the hood or similar element of a vehicle, such as a snowmobile, for the snagging, cutting, or breaking of wire, rope, or the like.

We claim:

The ornamental design for a vehicular safety device or the like, substantially as shown and described.
